Primary Examiner — Kelley A Donnelly(74) *Attorney, Agent, or Firm* — Brooks Kushman P.C.;
Lora Graentzdoerffer(57) **CLAIM**

The ornamental design for a retail display rack, as shown and described.

DESCRIPTION

FIG. 1 is a front, left perspective view of a retail display rack according to an embodiment;
FIG. 2 is a front, right perspective view of the retail display rack FIG. 1;
FIG. 3 is a front elevation view of the retail display rack of FIG. 1;
FIG. 4 is a left side elevation view of the retail display rack of FIG. 1;
FIG. 5 is a right side elevation view of the retail display rack of FIG. 1;
FIG. 6 is a top plan view of the retail display rack of FIG. 9 FIG. 1;
FIG. 7 is a bottom view of the retail display rack of FIG. 9 FIG. 1; and,
FIG. 8 is a rear elevation view of the retail display rack of FIG. 1.
The broken lines are for illustrative purposes only and form no part of the claimed design.
